TACKING STRIP

Otto Thiel, Detroit, Mich.

Application July 6, 1936, Serial No. 89,157

6 Claims. (Cl. 117—53.5)

This application relates to tacking strips for automobile upholstery and discloses an improved strip of greater density, pliability, hardness, and smoother finish than strips now in use.

5 An embodiment of the invention is shown in the accompanying drawing, in which

Fig. 1 is a perspective view of a section of tacking strip;

10 Fig. 2 is a perspective view of the strip of Fig. 1 with the various layers cut away and the paper unwound to show the construction.

Referring to the drawing it will be seen that the tacking strip consists of a core 10 about which is wound a wrapper of paper 11 which is in turn 15 encased by a thick coating of asphalt 12 which is covered by a skin or cover of paper 14.

20 The core 10 may be asphalted paper or untreated paper crushed into proper shape and laid straight.

25 The wrapper 11 may also be either plain or treated paper, formed into strips and wound spirally about the core. In the particular embodiment of the drawing the strips of the wrapper 11 have been crushed from flat thin 12 inch wide strips into narrow crushed strips of approximately one-half inch in width and one-eighth inch in thickness.

30 Encasing the wound wrapper 11 is a coating 12 of asphalt approximately one-sixteenth inch thick.

35 This is wrapped in a spirally wound paper cover or skin 14 which may be a single smooth thin wide strip one and one-half inches wide, continuously wound around the interior of the strip, or which may comprise several such strips overlapping each other, with each being continuously wound.

A principal characteristic of the present strip 40 is the presence of the layer of asphalt 12. Its presence helps form the strip components into a unitary and dense mass, and enables the strip to be made more dense than is an all-paper strip,

and permits the use of the skin tight cover or skin 14, thus providing a smooth thin skin for the strip, and permits the strip to be bent and twisted without unravelling.

Now having described my invention, reference 5 will be had to the claims which follow for a determination of the scope of the monopoly sought.

I claim:

1. In a tacking strip, a core, an encasing thick 10 coating of asphalt outside said core, and an outer skin of thin flat smooth paper ribbon.

2. In a tacking strip, a core, a spirally wound twisted paper wrapper thereon, an encasing thick coating of asphalt outside said wrapper, and an 15 outer skin of thin flat smooth paper ribbon.

3. In a tacking strip, a core, a spirally wound twisted paper wrapper thereon, and an outer skin of thin flat smooth paper ribbon wound spirally on the wrapper, there being an encasing thick 20 coating of asphalt outside the wrapper.

4. In a tacking strip, a core, a spirally wound twisted paper wrapper thereon, and an outer skin of thin flat smooth paper ribbon wound spirally on the wrapper, there being an encasing thick 25 coating of asphalt outside the wrapper and inside the skin.

5. In a tacking strip, a core, a spirally wound twisted paper wrapper thereon, and an outer skin of thin flat smooth paper ribbon wound spirally 30 on the wrapper with the two windings being oppositely wound, there being an encasing thick coating of asphalt outside the wrapper.

6. In a tacking strip, a core, a spirally wound twisted paper wrapper thereon, and an outer skin 35 of thin flat smooth paper ribbon wound spirally on the wrapper with the two windings being oppositely wound, there being an encasing thick coating of asphalt outside the wrapper and inside the skin.

40

OTTO THIEL.
